BUFFER MECHANISM FOR AUTOMATIC FIREARMS WITH BREECH MECHANISM LOCKED BY INERTIA

Hanns Lippert and Erwin Hepperle, Zurich, Switzerland, assignors to Verwaltungsgesellschaft der Werkzeugmaschinenfabrik Oerlikon, Zurich-Oerlikon, Switzerland, a firm

Application January 7, 1942, Serial No. 425,890
In Switzerland July 26, 1940

Section 3, Public Law 690, August 8, 1946
Patent expires July 26, 1960

1 Claim. (Cl. 89—198)

1

It is known in automatic fire-arms designed on the principle of breech-locking by inertia to provide spring buffers for the front and rear reversal of the breech block. The arrangement of these spring buffers encountered some difficulties. A construction is already known in which the spring buffer for the rear reversal is lodged in the breech bars. The general tendency, however, with increase in firing rate and of the initial velocity of the projectile is to bring down the weight of the moving masses, and therefore to transfer springs and other organs to the stationary parts. This requirement has already been taken into consideration in a known constructional example in which the spring buffers are lodged in the stationary parts, namely, in a cross-head fitted in the breech casing. In this arrangement the same springs can be used both for the front and rear reversal.

A drawback of this known arrangement resides in the fact that a special body must be provided, which is comparatively complicated in design and manufacture, rendering assembly more difficult.

The object of the present invention is an automatic fire-arm designed on the principle of breech-locking by inertia in which the provision of special parts for taking up the buffer springs is no longer necessary.

According to the invention the breech casing of an automatic fire-arm working on the inertia locking principle, in which a system of buffer springs is provided for damping the terminal forward and rearward movements of the breech block, is constituted of two parts screwed together and itself includes the buffer springs. The rear end of the buffer springs lies against a sleeve sliding in the breech-casing head and supporting itself against the breech-casing proper. With their front end the buffer springs are supported against a buffer piece slidingly fitted on a screwed-in ring. This buffer piece enters the breech-casing head with several buffer rammers through corresponding recesses.

A constructional example of a fire-arm according to the invention is shown on the attached drawing.

Fig. 1 shows the fire-arm at the moment of front reversal;

Fig. 2—at the moment of rear reversal of the breech block, and is a longitudinal section taken along a plane which is angularly displaced with reference to Fig. 1;

Fig. 3 is a section through the line A—A of Fig. 1;

Fig. 4—a section through the line B—B of Fig. 1;

2

Fig. 5—a section through the line C—C of Fig. 1.

The barrel 1 is inserted in the breech-casing head 3 by means of a bayonet joint 2. The breech-casing head 3 is screwed in to the breech-casing proper 4, and secured against rotation by means of the dovetailed locking bar 5. The springs 6 are lodged in borings in the breech-casing head 3. The sleeve 8 slides in a recess 7 in the breech-casing head 3. Its travel to the rear is limited by the breech-casing 4. The springs 6 are supported against the sleeve 8. A threaded ring 9 is screwed into the breech-casing head and on it glides an annular buffer piece 10 provided with several circumferentially spaced buffer rammers 11, the stroke of which is limited by the breech-casing head. The breech-casing head 3 is provided on the front end with recesses 12 into which penetrate the correspondingly shaped buffer rammers 11 of the buffer piece, and bear against the springs 6. The thread on the breech-casing head 3 by means of which the threaded ring 9 is inserted in the breech-casing head 3 is not continuous; it is only provided in the intervals between each two buffer rammers. Several springs 6a are lodged in borings in the breech-casing head which do not go all the way through and are therefore directly supported therein. These springs 6a only serve to damp the forward movement of the breech block.

At the end of its forward run the breech-block strikes the sleeve 8 which slides forward against the action of the springs 6 and 6a, whereby the impact of the breech is damped. After the round has been fired, the breech block recoils. Thereby the recuperation spring 14 which is supported against the threaded ring 9 is compressed by the spring casing 15 rigidly connected to the breech-block. Just before the recoiling parts reach their rear-most position, the spring casing 15 impacts upon the buffer piece 10. The latter slides rearwards and compresses the springs 6 via the rammers 11. This action dampens the rear reversal of the breech-block.

45 We claim:

In an automatic fire-arm of the type wherein the breech mechanism is locked by inertia and wherein a buffer spring system is provided for damping the terminal forward and rearward movements of the breech block, the combination, with the breech block, of a breech casing composed of a breech casing head and a breech casing proper threadedly connected together, the casing head having a plurality of circumferentially spaced through bores, a plurality of buffer springs housed directly in said bores, said casing head

having additional bores between the first-mentioned bores and open at the rearward ends and closed at their forward ends, additional buffer springs in said additional bores, a sleeve sliding in the breech casing head and supported against the breech casing proper, the buffer springs bearing at their rear ends against said sleeve, a ring threadedly connected with the breech casing head, and a buffer piece slidably fitted on said ring and provided with a plurality of circumferentially spaced buffer rammers penetrating in the first-mentioned bores of the breech casing head, the forward ends of the springs in such

first-mentioned bores bearing against said buffer ramers.

HANNS LIPPERT.
ERWIN HEPPERLE.
